TERMINAL CLIP STRUCTURE AND METHOD AND APPARATUS FOR APPLYING SAME

Edwin Grant Swick, Bartlett, Ill., assignor to Illinois
Tool Works, Chicago, Ill., a corporation of Illinois

Filed Nov. 8, 1955, Ser. No. 545,726

6 Claims. (Cl. 29—193.5)

The present invention relates to a novel clip structure for receiving and retaining elements such as terminal wires or prongs of electronic tubes or the like and to a novel apparatus for applying such clips to an apertured workpiece such as a printed circuit panel.

In accordance with conventional procedures heretofore adopted for manufacturing electronic equipment chassis and the like, terminal clips for prongs of electronic tubes were individually applied to a panel or individually assembled with a socket member of insulating material and the resulting assemblies were individually handled and applied to a workpiece or panel. As will be understood, the individual handling and assembly of these elements requires the expenditure of a considerable amount of time and labor. It is, therefore, an important object of the present invention to provide a novel terminal clip structure or the like whereby a plurality of individual clips or groups of clips may be handled as a unit and easily applied individually or simultaneously in groups to an apertured workpiece or panel.

Another important object of the present invention is to provide a novel apparatus for handling and applying to a work structure the novel clip elements of the present invention.

A more specific object of the present invention is to provide a novel terminal clip strip of simple and economical construction, and also to provide a novel apparatus for separating clip elements from such a strip and applying the separated clip elements to an apertured workpiece.

Another more specific object of the present invention is to provide a novel terminal clip structure especially adapted for application to printed circuit panels although other uses will suggest themselves, which clip structure is of simplified construction and is formed so as readily to receive tube prongs, terminal elements or the like and also securely to retain such prongs or elements. Other objects and advantages of the present invention will become apparent from the following description and the accompanying drawings wherein:

Fig. 1 is a plan view showing a novel terminal clip structure including a plurality of clip elements adapted to be separated from each other after the structure is applied to a workpiece;

Fig. 2 is a cross sectional view taken along line 2—2 in Fig. 1;

Fig. 3 is a fragmentary perspective view of the novel clip structure shown in Fig. 1;

Fig. 4 is a fragmentary plan view showing a novel terminal clip strip formed in accordance with the present invention and including a plurality of integrally connected clip structures of the type shown in Fig. 1, which clip structures are adapted to be formed after separation from the strip so as to provide angularly disposed stud portions and socket portions as shown in Figs. 1 through 3;

Fig. 5 is a plan view showing the clip structure of Fig. 1 applied to an apertured workpiece or panel;

2

Fig. 6 is a plan view showing the clip structure applied to the apertured panel and the individual clip elements separated from each other;

Fig. 7 is a fragmentary perspective view showing an individual clip element applied to an apertured panel;

Fig. 8 is a cross sectional view taken along line 8—8 in Fig. 6;

Fig. 9 is a cross sectional view similar to Fig. 8 and showing a radio tube or the like applied to the terminal clips;

Fig. 10 is a plan view showing a portion of a terminal clip strip embodying a modified form of the present invention;

Fig. 11 is a plan view showing a portion of another terminal clip strip formed in accordance with another modified form of the present invention;

Fig. 12 is a fragmentary plan view showing a further modified terminal clip strip;

Fig. 13 is a perspective view showing a completely formed terminal clip element separated from the strip shown in Fig. 12;

Fig. 14 is an elevational view showing an apparatus constructed in accordance with the present invention for handling the terminal clip strips and applying the terminal clips to an apertured workpiece;

Fig. 15 is a sectional view taken along line 15—15 in Fig. 14;

Fig. 16 is a sectional view taken along line 16—16 in Fig. 15;

Fig. 17 is a fragmentary sectional view similar to Fig. 16 but further showing how the apparatus functions to separate successive terminal clip structures from the strip, form the terminal clip elements and apply the clip elements to an apertured workpiece or panel;

Fig. 18 is a fragmentary sectional view taken along line 18—18 in Fig. 17; and

Fig. 19 is a sectional view taken along line 19—19 in Fig. 17.

Referring now more specifically to the drawings where like parts are designated by the same numerals throughout the various figures, Figs. 1 through 9 show one embodiment of the present invention which includes a clip structure 20 having a plurality of clip elements 22 initially integrally connected by a connecting section 24.

In order to facilitate handling of the clip structures prior to application of the clip structures to an apertured workpiece, a plurality of the clip structures 20 is initially formed in a strip 26 as shown in Fig. 4. More specifically, the clip structures 20 are stamped or otherwise formed from a sheet of stock material in a flattened condition and so that a pair of oppositely extending elements 22 of each clip structure is integrally connected with corresponding elements 22 of adjacent clip structures. It will be appreciated that the clip structure strip

55 may be easily handled and fed to a work station, and in accordance with another feature of the present invention, an apparatus which is described below is provided at a work station for separating and forming successive clip structures and applying the clip structures to an apertured workpiece. It will also become apparent

60 that the extremely simple construction of the clip structures facilitates their separation from the strip and application to a workpiece in the manner described below.

In Figs. 1, 2 and 3 the clip structure 20 is shown separated from the strip and formed so that it is ready for application to an apertured workpiece. When the clip structure is in this condition, each of the clip elements 22 includes a generally axially extending shank or finger portion 28 adapted to project through an aperture in a workpiece or panel, and a socket portion 30 for receiving a terminal wire, tube prong or other element to be retained. Each socket portion 30 is provided with a

generally radially extending slot 32 defined by opposite marginal portions 34 and 36 which are deformed downwardly at an acute angle to the remainder of the socket portion 30 so as to present downwardly and inwardly facing edges 38 and 40. These edges are adapted to bite into a terminal element or prong inserted through the slot so as to resist unauthorized removal of the terminal element and also to insure the provision of good electrical contact between the terminal element and the clip. It is understood, of course, that the clip structure is formed from any suitable sheet material or metal having the desired electrical conductivity characteristics.

In the particular embodiment illustrated, the clip structure 20 has seven clip elements 22 adapted to be applied to a printed circuit panel 42 or the like for receiving prongs 44 of a radio tube 46 or the like. However, it is understood that the number and arrangement of clip elements in each clip structure may be altered so as to accommodate wires or prongs of various devices. After a clip structure has been separated from the strip and the shank portions or fingers 28 have been formed to extend axially, the clip structure is applied to an apertured workpiece or printed circuit panel as shown in Fig. 5 and in the manner described fully herein below. It will be appreciated that this procedure enables all of the clip elements 22 of a clip structure to be applied to the workpiece simultaneously so as to eliminate individual handling thereof. The clip elements are subsequently separated from each other by severing the connecting portion 24 of the clip structure therefrom as shown in Fig. 6. The connecting section 24 is severed so that the slots 32 in each socket portion extend to the resulting terminal ends of the socket portions. As a result, each socket portion is provided with a pair of resilient sections at opposite sides of the slot, which sections spread apart to permit widening of the slot during insertion of a prong therein and subsequently resiliently and firmly urge the edges 38 and 40 into engagement with an inserted prong or other terminal element. The flexibility of the resilient sections may be increased, if desired, by providing an aperture 48 in each socket portion. The apertures 48 which intersect the slots 32 also serve to prevent the socket portions from cracking at the ends of the slots as a result of repeated flexing of the socket portions sections, as will be understood.

As shown in Fig. 8, solder or the like may be applied to portions of the shanks or fingers 28 extending through the workpiece or panel 42 to prevent the clip elements 22 from becoming disassembled from the panel, and when the panel 42 is a printed circuit panel, the solder 50 also serves to provide an electrical connection between the shank portions or fingers 28 and circuit elements 52 printed on the panel. The panel 42 is provided with an aperture 54 centrally located with respect to the slots through which the shanks 28 extend for accommodating the prongs 44 of the tube 46 and also for accommodating a punch or die used to separate the connecting section 24. The solder may be applied to the shanks or fingers 28 by dip-soldering in a known manner, and it should be noted that the socket portions of the clips are located entirely above the lower surface of the panel 42 so as to prevent the socket portions from being dipped into the solder and becoming clogged by the solder.

Fig. 10 shows a terminal clip strip 26a embodying a modified form of the present invention, which terminal clip strip is similar to the above described strip as indicated by the application of identical reference numerals with the suffix "a" added to corresponding elements. In this embodiment, a plurality of clip structures 20a are integrally interconnected by means of a laterally offset and longitudinally extending element 56 and connecting fingers 58 extending between the element or strip 56 and the connecting sections 24a of the clip structures. This embodiment enables the shank portions of the clip elements to be axially positioned before the clip structures are severed from the strip, if desired.

Fig. 11 shows another modified form of the present invention which is similar to the above described structures as indicated by the application of identical reference numerals with the suffix "b" added to corresponding elements. In this embodiment each of the clip structures 20b is initially provided with eight evenly spaced clip elements 22b which are arranged so that a pair of adjacent clip elements are disposed on opposite sides of the strip center line and are integrally connected with a similar pair of clip elements of an adjacent clip structure as indicated at 60 and 62. In addition, a pair of longitudinally extending connecting elements 64 and 66 is provided, which elements are arranged at opposite sides of the clip structures 20b and are integrally connected to opposite pairs of adjacent clip elements of each clip structure as indicated at 68, 70, 72 and 74. The terminal clip structures interconnected in the strip in accordance with this embodiment cannot be easily accidentally twisted relative to each other while at the same time, successive clip structures may be readily separated from each other and from the elements 64 and 66 with a single punching operation.

Figs. 12 and 13 show another embodiment of the present invention which is similar to the above described structures as indicated by the application of identical reference numerals with the suffix "c" added to corresponding elements. In this embodiment the terminal clip strip 26c comprises a series of single clip elements 22c rather than a series of circularly arranged groups of clip elements. It will be appreciated that the clip elements 22c may be readily separated from the strip along the lines 76 after which they may be formed in much the same manner as the clip elements described above. This embodiment has an advantage in that considerable savings in stock material may be effected and is particularly useful when the clip elements need not be applied to the panel in relatively large groups.

In Figs. 14 through 19 there is shown an apparatus 80 constructed in accordance with the present invention for separating the above described clip structures from the strips and applying the clip structures to the workpiece or panel. The apparatus 80 includes a punch press or the like of known construction having a base 82 and a reciprocable ram 84 which is actuated by suitable means, not shown. An adapter member or master punch holder 86 is secured to the lower end of the ram 84, which punch holder rotatably carries a head member 88. The rotary head 88 is provided with a plurality of axially extending apertures 90 which, in the embodiment illustrated, are spaced 180° from each other, and die assemblies 92 are disposed in the apertures 90. Each of the assemblies 92 includes an annular die 94 axially slidably disposed in the aperture 90 and retained against rotation relative to the head member by means of pins 96 and 98 mounted in the head member and extending through elongated slots 100 and 102 in the punch. An inserting tool 104 which functions in the manner described below is mounted within the punch and is held against both axial and rotational movement relative to the head 88 by the pins 96 and 98. A knockout pin 106 is slidably disposed in a bore through the inserting tool 104, and spring means 108 extends between the punch holder 86 and a laterally extending finger 110 of the knockout pin for normally retaining the knockout pin in an elevated inoperative position.

At one station on the base 82 there is secured die means 112 having a shearing die 114 cooperable with the die 94 to sever a clip structure from the strip, and a male former 116 cooperable with the die 94 to form the shanks 28 generally axially substantially simultaneously with the severing operation. A knockout ring 118 is disposed in the slot between the shearing die section 114 and the former 116, which knockout ring is resiliently urged upwardly by spring means 120. After

a clip structure has been severed from the strip and formed, the ring 118 causes the clip structure to be stripped from the former 116 so that the clip structure will be retained within the die 94 when the die is raised.

At another station on the base 82 there is secured a punch holder 122 on which is mounted a punch 124 and a table or pad 126 resiliently supported by spring means 128. A workpiece or panel 42 having preformed slots or openings 130 therein for receiving the clip element shanks is positioned on the table or pad 126 by any suitable means, not shown, and the rotary head 88 is indexed by means described below so that a die assembly 92 carrying a severed and formed clip structure 20 is positioned in axial alignment with the punch 124. Then upon the down stroke of the ram, the tool 104 presses the shank portions 28 of the clip elements through the slots 130, and the punch 124 enters the central bore in the tool 104 and severs the connecting section 24 from the clip structure as shown in Fig. 17. At the same time, another clip structure is severed from the strip and is formed also as shown in Fig. 17. It is necessary to retain the punch 94 at the severing and forming station above the die means 112 against upward movement while at the same time, it is necessary to permit the other punch member 94 at the clip element assembly and separating station to rise when it engages the panel or workpiece 42 so as to prevent injury to the panel. In order to accomplish this, the member 86 projects at least partially over the upper ends of the punches 94, and a cam surface 132 is provided at the under side of the member 86, which cam surface is substantially flush with the upper surface of the rotary head 88 adjacent the severing and forming station and is substantially spaced above the upper surface of the rotary head 88 adjacent the assembly and separating station. After each assembly and separation operation, the knockout pin 110 of the appropriate assembly 92 is actuated in the manner described below.

As shown in Fig. 15, guide means 134 which may be of any suitable construction is provided for directing a strip 26 or the like of terminal clip structures to the severing and forming station. Feeding means 136 which is schematically illustrated is provided for intermittently advancing successive clip structures of the strip to the severing and forming station in timed relationship with the reciprocable movement of the ram 84. The feeding means may, for example, include a reciprocable finger adapted to engage an edge or aperture of successive clip structures and positively advance the strip.

Means is provided for indexing the rotary head 88 in timed relationship with movement of the ram 84, and this means includes a friction roller 138 fixed on a rotatably mounted shaft 140 and engaging the periphery of the head 88. The shaft 140 is driven by an electric motor 142 or from any other suitable source of power through gears 144 and 146. A reciprocable locking pin 148 actuated by a solenoid 150 is provided for entering notches 151 and 153 in the rotary head and positively locating the head so that the assemblies 92 carried thereby will be properly aligned with the punches and dies on the base 82 after each time the head is indexed 180°. A reciprocable knockout actuating member 152 actuated by a solenoid 154 is provided for engaging the knockout pin 110 at the assembly and separating station during the upstroke of the ram so as to cause the separated connecting section 24 of a clip structure to be ejected.

The drive motor 142, the locating pin 148 and the knockout actuating member 152 are operated in timed relationship with each other and with the movement of the ram by suitable means such as that shown schematically in Fig. 14. More specifically, a switch 156 having an actuating plunger 158 is located so that the plunger is operated by a cam member 160 fixed on the ram. The switch 156 is electrically connected with a time-

delay switch 162 of known construction, which time-delay switch, when energized upon closing of the switch 156, serves to connect the motor 142 with a source of power and then to disconnect the motor after the passage of a predetermined interval of time. The switch 156 is also electrically connected with another time-delay switch 164 which, in turn, is electrically connected with the solenoid 150. The solenoid 150 is spring biased so that when it is deenergized the locating pin 148 is retracted from the locating slots on the periphery of the rotatable head 88. The time-delay switch 164 after being energized upon closing of the switch 156 functions to disconnect the solenoid 150 from a source of power so that the locating pin 148 is retracted. After the passage of a predetermined time interval, the switch 164 connects the solenoid 150 with the source of power so that the locating pin 148 is extended, which pin rides on the periphery of the rotatable head 88 until the head is turned sufficiently to align one of the locating slots 20 with the pin whereupon the pin enters the slot.

The solenoid 154 is spring biased so that when it is deenergized the actuating member 152 is held in the retracted position shown in Fig. 14. The solenoid 154 is also connected with the switch 146 so that it is energized upon closing of the switch so as to shift the member 152 into position for engagement with a knockout pin 110 during the initial portion of the upward stroke of the ram.

A brief resume of the operation of the apparatus 30 is as follows. With the elements of the apparatus in the positions shown in Figs. 14 and 16, a strip of terminal clips is positioned with the leading clip at the severing and forming station and a workpiece or panel 42 is located at the assembly and separating station. Then the 35 ram 84 is actuated downwardly so that the leading clip structure is severed from the strip and formed in the manner described above. As the ram approaches the lower limit of its stroke, the plunger 158 of the switch 156 rides up on the cam 160 so that the switch 156 is closed and the time delay switches 162 and 164 and the solenoid 154 are energized. As the ram then begins its 40 upward stroke after the motor 142 has been energized, the locating pin 148 has been retracted and the actuating member 152 has been extended, the friction drive 45 wheel 138 starts to index the rotatable head 88 and the actuating member 152 engages the knockout pin 110 disposed therebeneath. As the ram continues its upward movement, the locating pin 148 is extended in the manner described above, and the plunger 158 of the switch 50 156 rides off of the cam 160 so that the solenoid 154 is deenergized and the actuating member 152 is retracted to clear the advancing knockout pin 110. The locating pin 148 then enters an advancing locating notch or slot 55 in the periphery of the rotating head, and the time delay switch 162 functions to deenergize the drive motor 142. During the upward stroke of the ram, the strip feed means 136 functions to advance the next clip structure to the severing and forming station. Then the above 60 described cycle is repeated and the previously formed clip structure is applied to the panel 42 and the individual elements of this clip structure are separated from each other at the assembly and separating station. The cycle is repeated as often as necessary for applying the desired 65 number of clip structures to an apertured panel, and it is understood that suitable means, not shown, may be provided for feeding or locating the panel to locate different groups of preformed clip-receiving apertures at the assembly and separating station.

While the dies and punches shown in Figs. 16 through 70 19 have been specifically formed for use in connection with the above described strip 26 and clip structure 20, it is understood that the dies and punches may be modified for use with the other above described or similar terminal clip strips. For example, when the strip 26a 75 is to be used, the annular punch and former 94 may be

provided with a slot for accommodating the connecting fingers 58 so that these connecting fingers may subsequently be separated from the clip structures along with the central connecting section 24a. When the strip 26b is to be used, a similar slot or recess may be provided in the punch 94 so that one of the eight clip elements of each of the clip structures may be left unformed and may be subsequently separated with the central connecting section 24b, if desired.

While the preferred embodiments of the present invention have been shown and described herein, it is obvious that many structural details may be changed without departing from the spirit and scope of the appended claims.

The invention is claimed as follows:

1. A sheet metal strip of terminal clips or the like comprising a series of substantially flat clip structures including a plurality of circularly arranged clip elements integrally connected by a central connecting section, clip elements of each of said clip structures adjacent a longitudinal axis of said series being integrally connected with similarly located clip elements of an adjacent clip structure, said last mentioned integrally connected clip elements being severable for permitting the clip structures to be applied to an apertured workpiece, each of said clip elements including a socket portion for overlying one side of a workpiece for receiving a terminal element or the like and integrally joined directly to one of said central connecting sections and a finger portion integral with and extending from the socket portion for insertion through a workpiece aperture from said one side of said workpiece, each of said socket portions having slot means therein for receiving a terminal or the like, each of said slot means extending through an adjacent connecting section, said slot means normally having a width less than the width of a terminal to be received therein, said central connecting sections of said clip structures being severable from the clip structures after the clip structures have been applied to a workpiece so as to separate the clip elements from each other and to open ends of said slot means for facilitating spreading of the slot means for accommodating a terminal.

2. A sheet metal strip of terminal clips or the like, as defined in claim 1, wherein said clip elements adjacent said axis are substantially bisected by said axis, and wherein said last mentioned clip elements provide the only connection between adjacent groups of clip elements.

3. A sheet metal strip of terminal clips, as defined in claim 1, wherein each of said clip structures includes a pair of clip elements adjacent to and at opposite sides of said axis and integrally connected with a similarly located pair of clip elements of an adjacent clip structure.

4. A sheet metal strip of terminal clips, as defined in claim 3, which includes a longitudinally extending ele-

ment at one side of the strip and integrally connected with generally laterally extending clip elements of each of said clip structures so as to reduce any possibility of said clip structures twisting relative to each other.

5. A sheet metal terminal clip or the like for application to an apertured workpiece comprising a generally axially extending finger portion for insertion into a workpiece aperture from one side of a workpiece, and an integral socket portion extending laterally from said finger portion for overlying said one side of a workpiece, said socket portion having slot means therein for receiving a terminal element or the like and having one end extending to a free terminal end of said socket portion, one of said portions including enlarged aperture means therein intersecting an opposite end of said slot means, said slot means being defined by elements between opposite ends thereof inclined downwardly from an upper surface of said socket portion at an acute angle to an axis of the slot means disposed substantially normally to said socket portion and providing relatively sharp upper corner edges closer together than lower corner edges for engagement with a terminal element or the like for restraining removal of said terminal element or the like from the slot means, said upper edges initially being spaced apart a distance less than the width of a terminal element or the like to be inserted therebetween, and sections of said socket portion at opposite sides of said slot means being resiliently yieldable to permit spreading of said upper edges during insertion of a terminal element or the like therebetween and for resiliently urging said upper edges into engagement with an inserted terminal element or the like.

6. A sheet metal terminal clip structure including a plurality of terminal clips as defined in claim 5, said terminal clips being generally circularly arranged, and a centrally disposed connecting section integrally connecting said terminal clips for facilitating simultaneous application of said terminal clips to an apertured workpiece, said connecting section being severable from said terminal clips to separate the terminal clips on a workpiece from each other.
